UNITED STATES PATENT OFFICE.

CAVAN HENDERSON, OF BOSTON, MASSACHUSETTS, ASSIGNOR OF ONE-HALF TO JOHN W. HORNE, OF SAME PLACE.

COMBINATION-LOCK.

SPECIFICATION forming part of Letters Patent No. 387,300, dated August 7, 1888.

Application filed January 24, 1888. Serial No. 261,796. (No model.)

To all whom it may concern:

Be it known that I, CAVAN HENDERSON, of Boston, in the county of Middlesex and State of Massachusetts, have invented a new and useful Improvement in Combination-Locks, of which the following is a full, clear, and exact description, reference being had to the accompanying drawings, forming a part of this specification, in explaining its nature.

The object of the invention is to provide a combination-lock of simple, inexpensive, and compact construction.

In the drawings, Figure 1 is a view, in elevation, of a box having my combination-lock attached thereto. Fig. 2 is a view, in elevation, of a portion of a box, the front plate of the lock being removed to show the interior construction thereof, and representing the position of the parts when locked. Fig. 3 is a view of the same parts, showing their position when unlocked. Fig. 4 is a vertical section of a portion of the box and lock enlarged. Fig. 5 is a view in horizontal section, enlarged, of a portion of the lock. Figs. 6, 7, and 8 are views of the tumblers employed. Fig. 9 is a view of the washer which is interposed between the tumblers.

Referring to the drawings, A represents the case of the lock.

a is a slide-bolt mounted on one plate of the lock, and represented as formed upon the slide-plate a². This slide-plate is moved by a lever, a³, attached to a shaft or turning-stud, a⁴, which extends to a position on the outside of the front plate of the lock, and has a finger-piece, a⁵, or other end by which it may be easily turned. The stud a⁴ is the fulcrum of the lever a³, and the lever is connected with the slide-plate a² by means of a pin, a⁶, secured to said plate, and which extends into a long recess, a⁷, at the outer end of the lever a³. The bolt a is formed by cutting or removing a section of the plate a² to form the recess a⁷. (See Fig. 3.)

B B' B² represent tumblers. They are annular in shape, and each has an opening, b. The tumbler B has the inward projection or tooth b', the tumbler B' the inward projections or teeth b² b³, and the tumbler B² the projections b⁴ c⁵, which form a recess, b⁶. These tumblers are held in a cylindrical case, C, secured to the inner plate, c, of the lock, said case being

of a size to hold the tumblers and permit them to be turned therein, and the tumblers are separated from each other by annular washers D, each of which has an opening, d, and an outward extension or tongue, d', which enters a recess, d², in the casing C. This construction prevents the washers from being turned upon the turning of the tumblers, and always maintains the openings d in line with the opening d² of the case C.

The tumblers B B' B² are operated by means of a spindle, E, which extends from the operating-button e through the cavity of the tumblers and washers, and has a bearing in the case-plate c. This spindle has extending from it an arm or wing, e', which enters the recess b⁶ of the lower tumbler, B, between the projections b² b³ of the tumbler B', and extends to come in line with the projection b' upon the tumbler B; and in order to set the tumblers to allow the bolt to be moved it is necessary that the spindle should be first moved or turned in one direction to bring the opening b of the tumbler B in line with the opening d² in the case C, and then that its movement should be reversed in order that the second tumbler B' should be moved to bring its opening b in line with the opening d², and then to be again turned in the direction in which it was first turned to move the tumbler B² sufficiently to bring its opening b in line with the said opening d².

There is attached to the arm of the slide-plate a² a thin locking-bar, f, preferably integral with the plate, and which is of a size to enter the opening d² in the case C and the openings b of the tumblers when they are moved into line with the said opening d², and when they are so moved, by turning the stud a⁴, the bolt a may be moved, the locking-bar f being unobstructed and riding freely into the openings d² b. If, however, one or more of the tumblers should be so turned as to close the opening d², of course the locking-bar cannot then be turned or moved by the spindle. I prefer to make the outer end of the spindle square, as represented in Fig. 5, and to form in its operating-button a square hole for its reception. By this connection there is provision for four different connections between the dial and the spindle.

F is the dial. It is divided into any desired number of spaces, which are numbered or let-

tered, and there is arranged upon the escutcheon-plate of the lock a line or indicator, to which a numbered or lettered line of the dial is moved in setting the tumblers.

5 The advantages of the construction arise very largely from its simplicity, from its compact form, and from its cheapness.

Having thus fully described my invention, I claim and desire to secure by Letters Patent 10 of the United States—

1. The combination, in a combination-lock, of the slide-plate, having a bolt, a , and the locking-bar f , means for moving the slide-plate and bar, the tumbler-casing C , having the opening 15 d^3 , the annular tumblers $B B' B^2$, or two or more of them, having the openings b , and the projections or teeth, as specified, and the operating-spindle E , having the wing e' , which engages the projections of the tumblers, as and 20 for the purposes described.

2. The combination, in a combination-lock, of the tumbler-case C , the annular tumblers $B B' B^2$, having the openings b and inward-extending projections, and the washers D , having the openings d and holding-extensions d' , substantially as described.

3. The combination of the slide-plate a^2 , the bolt a , the locking-bar f , the stud a^4 , lever a^3 , connecting the stud with the said slide-plate, the tumbler-case C , having the opening d^3 , 30 the tumblers $B B' B^2$, having openings b and projections, as specified, the washers D , having the openings d and extensions d' , and the operating-spindle E , having the wing e' , substantially as described.

4. The combination, in a combination-lock, of the tumbler-case C , having the openings d^3 d^2 , the tumblers $B B' B^2$, having the openings b and projections, as specified, the washers D , having the openings d and locking-extensions 40 d' , the spindle E , having the wing e' and a square head, with the button e , having a square hole to receive the end of the spindle and permit it to be adjusted into other positions in relation thereto, substantially as described.

CAVAN HENDERSON.
